UNITED STATES PATENT OFFICE

108,718

DESIGN FOR A COMBINATION HOT WATER AND ICE BAG

Ernest I. Kilcup, Barrington, R. I., assignor to Davol Rubber Company, Providence, R. I., a corporation of Rhode Island

Application November 20, 1937, Serial No. 73,053

Term of patent 14 years

To all whom it may concern:

Be it known that I, Ernest I. Kilcup, a citizen of the United States, residing at 6 Elton Road, Barrington, Rhode Island, in the county of Bristol and State of Rhode Island, have invented a new, original, and ornamental Design for a Combination Hot Water and Ice Bag, of which the following is a specification, reference being had to the accompanying drawing, forming part thereof.

In the drawing:

Fig. 1 is a plan view of the novel combination hot water and ice bag showing my new design;

Fig. 2 is a rear view thereof; and

Fig. 3 is a side view thereof.

I claim:

The ornamental design for a combination hot water and ice bag as shown.

ERNEST I. KILCUP.
